UNITED STATES PATENT OFFICE

2,460,917

SAFETY BOOTH

John W. Beretta, San Antonio, Tex.

Application August 8, 1947, Serial No. 767,551

9 Claims. (CL. 109—19)

1

This invention relates to safety booths or enclosures for tellers, cashiers or clerks in banks or other similar places where money, valuable papers or packages are received from and delivered directly to persons outside of the bank itself while affording mutual visibility and means of vocal communication between the teller and persons outside the booth and for protecting tellers from exposure to outside weather conditions and from such activities as would occur in the event of an attempted or actual "hold-up." It relates more particularly to "drive-in" booths where persons may approach in automobiles or other vehicles and transact necessary business with the teller or clerk conveniently without leaving the vehicle. The use of this invention may also be applied to ticket offices, stores, loan agencies, public service and utility establishments, tax collection offices, payroll offices, or similar institutions where public convenience is indicated and security or weather protection is necessary. Variations of this invention may also be applied to armored vehicles used to transport money or other valuables where it is necessary to obtain added safety and security for such operations. The principal object of this invention is to provide such a booth, through the bullet-resistant and weather shielding of which, articles of value may be passed quickly and readily without at any time exposing the teller or clerk to armed threats or violence or to outside weather conditions.

The features of this invention include a pivoted bin, mounted adjacent to an opening in a tellers or cashiers counter, adapted to be swung out through a wall from the counter of the booth and provided with a bullet-resistant side, front, back and bottom metal plates, a removable metal tray and a movable, bullet-resistant metal cover member, the bin and its cover being so constructed and arranged, and so manipulated and controlled, that the teller at his counter is never physically exposed to outside weather conditions or to any persons outside of the booth, although mutual visibility is afforded by means of bullet-resistant glass windows, means of vocal communication is provided by telephonic or similar means, and protection from the effects of inclement weather outside the booth is provided by weather stripping, drip troughs, shields, gaskets, or similar devices around the bin.

Other objects and features will appear from the following description taken in conjunction with the accompanying drawings in which

2

Fig. 1 is a front elevational view from the outside of the booth;

Fig. 2 is a plan view of the booth taken on line 2—2 of Fig. 1;

Fig. 3 is an enlarged vertical cross-sectional view of the booth, taken on line 3—3 of Fig. 1, including the bin and operating mechanism;

Fig. 4 is an enlarged detailed plan view of certain parts of the bin and booth of Fig. 3;

Fig. 5 is a further enlarged view showing details of the cover and its operating mechanism; and

Fig. 6 is a detail illustrating the locking of the treadle lever.

In elevation, the front of the booth, Fig. 1, consists of bullet-resistant wall 1, windows 2 composed of a bullet-resistant glass, suitably framed in, and preferably flush with the outer surface of the wall, and bullet-resistant metal front plate

20 3 of a bin hereinafter described.

Inside the booth, Fig. 2, is a counter or desk 4 abutting the wall 1 and facing the windows 2.

Through the middle of the front edge portion of the counter 4 is aperture 5. Directly in line with 25 this aperture 5, down through window-sill 6 under windows 2 to the level of the bottom edge of the plate 3 and out through the wall 1 is an opening 7, which is framed by metal angles 7a, and which is covered on the outside by the plate 3, 30 in its rearward position, the side edges of which fit into the metal framing of the opening 7 in the wall 1.

Under the aperture 5 and opening 7, extending back under the counter 4, Fig. 3, is a bin, generally designated by reference character 9.

This bin 9 is composed of bullet-resistant metal plates, namely, the front plate 3, side plates 10, back plate 11, and bottom plate 11a, the latter two together providing a rearward protective plate.

At the respective top curved edges of the side plates 10 and along the same are mounted curved, grooved guide members 12, with rearward extensions 12a, the latter being affixed at their rearward ends to the tops of braces 13, 45 all of which parts provide the bin unit and swing with the bin. Within the front, side and back plates at a suitable depth is located a removable tray 14. This removable tray 14 may be provided with finger holes or other means to facilitate its removal by the teller when it is found necessary and expedient to provide a deeper and roomier receptacle to accommodate bags of coins or other bulky packages. The bin 9 is pivotally mounted

50 on rod 15, held in bearings 15a, affixed on the bottom metal framing of opening 7 in wall 1 so

that the bin 9 is swingable about the axis of the rod 15. A curved bullet-resistant metal plate cover 16 is slidably mounted in the grooved members 12 and 12a so as to be freely movable therein to its respective covering and uncovering positions. This cover 16 enables the complete closure of opening 7 as bin 9 moves forwardly or backwardly thus preventing exposure of the teller to outside weather conditions or to threats or bodily harm from the outside of the booth. In its outward position it also provides a convenient surface on which the customer may rest documents when writing is necessary. A further use of this cover 16 is to retain money or other valuable papers in the tray 14 until opened by the teller thus preventing gusts of wind from blowing such articles from the bin until delivery is completed and also to minimize the entrance of moisture into the bin 9 during inclement weather while it is in its forward position. Between the rearward extensions 12a is a curved fixed metal plate 12b which covers aperture 5 when the bin 9 and cover 16 are both in their outermost positions to prevent objects from falling through aperture 5. When the bin 9 is in its forward or outward position the tray 14 is inclined toward the customer which provides better visibility and accessibility for the customer. When the bin 9 is in its rearward or closed position the tray 14 is inclined toward the teller which provides better visibility and accessibility for the teller.

As shown in solid lines in Figs. 3 and 4, the bin 9 is drawn rearward so that the front plate 3 thereof, is flush with the wall 1, and the cover 16 is over the tray 14. The dotted lines of Fig. 3 show the forward or outermost position of the bin 9 when it is swung forward from the wall toward the customer on the outside of the booth. The slideable cover 16 is actuated through a curved rack 17 affixed thereto, as illustrated in Figs. 3, 4 and 5. Meshing with the rack 17 is pinion 18, on an axle mounted in suitable bearings affixed to plate 11 so as to move with bin 9. When pinion 18 is rotated by means of flexible shaft 18a and crank 18b, the cover 16 is driven forwardly and backwardly, as desired, to cover or uncover the bin 9 in its outermost, intermediate, or innermost positions. The bodily movement of the bin 9 itself is readily accomplished through any suitable means, for example, as shown by the treadle 19 which actuates, through the pin and slot connection shown in Fig. 3, the bell-crank 20, the upper end of which is pivoted to the bin 9. The bin 9 is pulled from its forward or outward position by the spring 21 when the force exerted by the teller's foot is released from treadle 19. The bin 9 is normally held in its rearward position by its own weight which applies the necessary force through its center of gravity, although it may also be locked in its rearward position (see the full lined and cross-hatched positions in Figs. 3 and 6 respectively) when the treadle 19 is moved sideways over the projection 22 of the slotted treadle guide 23. The bin 9 may also be locked in its outermost position upon depression of the treadle (see the dotted position in Figs. 3 and 6) and movement sideways under the projection 22 of the slotted treadle guide 23. The movement of the bin 9 is limited in its outer and inner positions, as shown in Fig. 3, respectively by the stops 24, 24a and 27.

In Figs. 3 and 4, are shown stop bars 24 and 24a affixed respectively to framing angles 1a and the bottom angle of the window sill. Across the

top and along the two sides of front plate 3 are affixed gaskets 26 of rubber or similar elastic material so placed as to securely contact the front of stop bars 24 and 24a, when front plate 3 is in the rearward or closed position. This serves the dual purpose of providing a weather seal when bin 9 is in its rearward or closed position and also providing a cushioned stop as bin 9 reaches its rearward or closed position. To provide weather protection as bin 9 and cover 16 are moved through various rearward and forward positions, flexible weather stripping 25 of felt, leather, impregnated fabric or similar materials, is affixed to the inner side of stop bars 24 and 24a. This weather stripping is so placed as to closely contact or rub against side plates 10 and cover plate 16 as they are moved through various rearward and forward positions, thus providing a weather seal at all times regardless of their position. To prevent moisture from dripping from the outside of windows 2 into bin 9 as it opens from its rearward to its forward position, a curved metal drip trough 28 is affixed to the outside of the bottom of the metal window frame as shown in Figs. 1 and 3. To prevent moisture, dirt or other foreign matter from entering the space at the bottom of plate 3, a bent metal shield or hood 29 is affixed to the bottom of plate 3 as shown in Figs. 1 and 3. To provide a cushioned and positive stop as bin 9 reaches its outermost position, stop angles 27 with affixed bumpers of rubber or other elastic material are provided as shown in Figs. 3 and 4, to contact frame angles 1a as bin 9 reaches its outermost position. To reduce the noise and to cushion the operation of plate 16 as it reaches its rearward and forward stopping positions, bumpers of rubber or other elastic material are placed on plates 3 and 12b in such a position as to prevent metallic contact.

When the booth is used as a "drive-in" facility where persons may approach in automobiles or other vehicles and transact business with the teller conveniently without leaving the vehicle it is necessary to provide a means of preventing contact between the booth and the bin 9 and the vehicle. Such contact might be harmful to the vehicle and the booth or the bin 9 and might possibly result in serious damage to one or the others. Such a means of preventing contact is a suitable curb 30 constructed of concrete or similar materials. Such a curb is constructed in two steps as shown in Figs. 1, 2 and 3, which are scientifically proportioned so that in case of extremely careless operation of the vehicle, the pneumatic rubber tires of the vehicle can climb only the first step of the curb and cannot obtain enough traction to climb the second step, thus completely preventing contact between the vehicle and the booth or the bin 9. Under actual tests in a successfully operating installation the pneumatic rubber tires of a modern automobile were repeatedly deflected back to the roadway after climbing the first step of the curb and contact between the vehicle and the booth were prevented. This curb 30 is also dimensioned and proportioned so as to enable and aid the driver of a vehicle to bring his vehicle sufficiently close to the bin 9 to make it readily and conveniently accessible from the vehicle window. The sloping position of plate 3 in its outermost or forward position is also designed to clear the bulging fenders and bodies of modern automobiles when they are driven close to the curb 30.

Vocal communications between the customer

outside and the teller inside the booth may be accomplished through the use of bullet-resistant speaking ports or any suitable two-way telephonic apparatus (not shown) either placed in the window or the wall 1, or other positions, convenient and practical.

Mutual visibility between the teller and the person outside the booth is provided by means of bullet-resistant glass windows 2 as shown in Figs. 1 and 2 with bin 9 mounted under them. In order to operate the bin 9 and to carry on the necessary business transactions the teller must stand in a position so that his actions are visible to the person outside the booth. In order to place money or other valuable papers into bin 9 the person outside the booth must be in a position of full visibility to the teller inside the booth. This feature is necessary and desirable in banks or similar institutions where the counting of money and verification of documents must be done in the presence of and within the vision of the interested parties.

Though the device has been successfully used with the manual or human operated and motivated controls and mechanisms as above described, in installations where the expense is warranted it can be readily operated electrically by suitable reversible electric motors, reduction gearing, cranks, overload and limit switches, or other devices with push button or other controls, as well understood by those versed in electrical art. Such an installation has already been made and has proved to be rapid, efficient and convenient in actual banking transactions where "drive-in" service is provided. The device may be constructed for motivation and control by other hydraulic mechanical, or electrical mechanisms, or a combination of same as well understood by those versed in such arts. The device can also be constructed as a "packaged" or self-contained unit with all controls and operating mechanisms shop assembled and properly enclosed and contained so that the bin unit can be removably mounted in a metal frame in a wall with bolts or other removable attachments. When so constructed the device would be easily removable for repair or replacement.

When the booth is not in operation the bin 9 is kept in its rearward or closed position and is locked in such position to prevent tampering from the outside of the booth. When the booth is in operation the bin 9 is kept in the same position until a person outside the booth approaches to utilize its facilities. When the person outside the booth arrives in the proper position the teller operates crank 18b to move cover 16 to its forward or closed position, following with the depression of treadle 19 which moves bin 9 to its forward position, after which crank 18b is turned in the opposite direction of move cover 16 to its rearward or open position. The person outside the booth may then place money or other valuable papers in tray 14, after which the teller again operates crank 18b to move cover 16 to its forward or closed position enclosing the articles in bin 9, following with the release of force on treadle 19 allowing spring 21 to pull bin 9 into its rearward position, after which the teller again turns crank 18b to move cover 16 to its rearward or open position exposing the material placed in bin 9 for the teller's necessary action. For delivery of money or valuable papers from the teller to a person outside the booth the procedure may be reversed. The simplicity of controls and operation of this device permits other sequences and varia-

tions of operation to meet special conditions as they arise and such operational variations may be left to the discretion of the teller. When the person outside the booth indicates that he has bags of money or bulky packages to place in bin 9, the teller removes tray 14 from bin 9 to provide a deeper receptacle before following the other necessary operational procedures, and on completion of the operation can replace the tray 14 in bin 9 before serving the next customer.

Thus, the booth of this invention is so impervious to attack and outside weather conditions that it may be used as an extension of a bank or other similar place where papers of value are interchanged, up to which automobiles or other vehicles may be driven, and occupants thereof readily transact their business with a bank teller or clerk.

It is to be understood that the appended claims shall be taken to mean and include armored vehicles which are in effect safety booths, as well as fixed safety booths or enclosures in banks or the like.

I claim:

25. 1. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side, and rearward protective plates extending rearwardly from said front plate, and a bullet-resistant cover member slidably mounted on said bin and selectively movable to cover and uncover said bin in either of its said outer and inner positions.
30. 2. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side, and rearward protective plates extending rearwardly from said front plate, and a bullet-resistant cover member slidably mounted on said bin and selectively movable to cover and uncover said bin in its outer and inner positions.
35. 3. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side, and rearward protective plates extending rearwardly from said front plate, a bullet-resistant cover member slidably mounted on said bin and selectively movable to cover and uncover said bin in its outer and inner positions, and weather and moisture sealing around and on said bin.
40. 4. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side, and rearward protective plates extending rearwardly from said front plate, and a bullet-resistant cover member slidably mounted on said bin and selectively movable to cover and uncover said bin in its outer and inner positions, and weather and moisture sealing around and on said bin.
45. 5. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side, and rearward protective plates extending rearwardly from said front plate, and a bullet-resistant cover member slidably mounted on said bin and selectively movable to cover and uncover said bin in its outer and inner positions, and weather and moisture sealing around and on said bin.
50. 6. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side, and rearward protective plates extending rearwardly from said front plate, and a bullet-resistant cover member slidably mounted on said bin and selectively movable to cover and uncover said bin in its outer and inner positions, and weather and moisture sealing around and on said bin.
55. 7. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side, and rearward protective plates extending rearwardly from said front plate, and a bullet-resistant cover member slidably mounted on said bin and selectively movable to cover and uncover said bin in its outer and inner positions, and weather and moisture sealing around and on said bin.
60. 8. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side, and rearward protective plates extending rearwardly from said front plate, and a bullet-resistant cover member slidably mounted on said bin and selectively movable to cover and uncover said bin in its outer and inner positions, and weather and moisture sealing around and on said bin.
65. 9. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side, and rearward protective plates extending rearwardly from said front plate, and a bullet-resistant cover member slidably mounted on said bin and selectively movable to cover and uncover said bin in its outer and inner positions, and weather and moisture sealing around and on said bin.
70. 10. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side, and rearward protective plates extending rearwardly from said front plate, and a bullet-resistant cover member slidably mounted on said bin and selectively movable to cover and uncover said bin in its outer and inner positions, and weather and moisture sealing around and on said bin.

movable to cover and uncover said bin in either of its outer, intermediate, or inner positions.

5. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side and rearward protective plates extending rearwardly from said front plate, a bullet-resistant cover member slidably mounted on said bin and selectively movable to cover and uncover said bin in either of its said outer and inner positions, and a removable tray inside of said bin.

6. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side and rearward protective plates extending rearwardly from said front plate, parallel grooved members extending along the upper edges of said side plates, and a bullet-resistant cover member slidably mounted on said bin and selectively movable in said grooved members to cover and uncover said bin in its said outer and inner positions.

7. In a booth for tellers or cashiers having a bullet-resistant wall, a bullet-resistant window framed in said wall and a wall opening through said wall adjacent said window, the combination of a movable bin adapted to be moved to outer and inner positions, a pivotal mounting for said bin within said wall opening, said bin comprising bullet-resistant front, side and rearward protective plates extending rearwardly from said front plate, parallel grooved members extending along the upper edges of said side plates, a bullet-resistant cover member slidably mounted on said bin and selectively movable in said grooved mem-

bers to cover and uncover said bin in its said outer and inner positions, and rack and pinion members adapted and arranged to move said cover.

8. In a booth for tellers or cashiers having a bullet-resistant wall, a bullet-resistant window framed in said wall and a wall opening through said wall adjacent said window, the combination of a counter, a movable bin adapted to be moved to outer and inner positions, a pivotal mounting for said bin within said wall opening and with the top of said bin movable adjacent said counter and directly accessible therefrom, said bin comprising a bullet-resistant front plate and rearward protective plates extending rearwardly from said front plate, and a bullet-resistant cover member slidably mounted on said bin and selectively movable to cover and uncover said bin in either of its outer and inner positions.

10 9. In a booth for tellers or cashiers having a bullet-resistant wall, a bullet-resistant window framed in said wall and a wall opening through said wall adjacent said window, the combination of a counter, a movable bin adapted to be moved to outer and inner positions, a pivotal mounting for said bin within said wall opening and with the top of said bin movable adjacent said counter and directly accessible therefrom, said bin comprising bullet-resistant front plate and plates 25 extending rearwardly from said front plate, a bullet-resistant cover member slidably mounted on said bin and selectively movable to cover and uncover said bin in either of its outer and inner positions, and weather and moisture sealing between said bin and said wall opening.

JOHN W. BERETTA.
